(57) **CLAIM**
What is claimed is the ornamental design for a telescoping handle, as shown and described.

DESCRIPTION

FIG. 1 is a perspective view of a handle, according to an embodiment of the present design;

FIG. 2 is another perspective view of the handle of FIG. 1;

FIG. 3 is a front elevation view of the handle of FIG. 1;

FIG. 4 is a rear elevation view of the handle of FIG. 1;

FIG. 5 is a first side elevation view of the handle of FIG. 1;

FIG. 6 is a second side elevation view of the handle of FIG. 1;

FIG. 7 is a top plan view of the handle of FIG. 1; and,

FIG. 8 is a bottom plan view of the handle of FIG. 1.

The broken lines showing portions of the handle are for the purposes of illustrating environment and form no part of the claimed design.
